UNITED STATES PATENT OFFICE.

JOSEPH MONTÖ, OF CLEVELAND, OHIO.

GALVANIZING APPARATUS.

1,124,785.

Specification of Letters Patent.

Patented Jan. 12, 1915.

Application filed July 30, 1913. Serial No. 781,997.

To all whom it may concern:

Be it known that I, JOSEPH MONTÖ, a citizen of the United States, and a resident of Cleveland, in the county of Cuyahoga and State of Ohio, have invented a new and useful Improvement in Galvanizing Apparatus, of which the following is a specification.

This invention relates to the art of coating metals,—as for instance,—galvanizing.

Many features of my present invention are applicable to coating metals in general, regardless of the character or conformation thereof, although, in the accompanying drawings, the invention is shown as embodied in an apparatus more especially adapted to galvanizing or otherwise coating open-ended receptacles formed of sheet metal, such, for instance, as pails.

An object of this invention is to regulate the depth or thickness of the coating applied and, preferably, without materially changing or modifying the speed of the coating process; and, also, to provide means whereby all of the articles to be coated may receive a practically uniform and predetermined depth of the coating to be applied thereto.

Another object is to provide for the removal of the matter usually floating on the surface of the molten bath at the point where and just before the articles being coated are withdrawn from the bath.

A further object is to provide means for more rapidly chilling the articles as they are withdrawn from the bath in order that the molten metal may be more rapidly set thereon as and just after they are removed from the bath.

Still another object is to provide means for automatically delivering the articles to be coated to an immersing cradle, the operation of which tends to force the articles therefrom as they are being immersed and which, after being immersed, are allowed to rest upon a grid along which they are forced by automatically operating mechanism and delivered to the withdrawing cradle which raises them to a position where they are each grasped by the gripping fingers on the withdrawing arm which latter carries and delivers them onto a suitable support from which they are later removed by the attendant. During the operation of the withdrawing arms, and while the articles are engaged and held thereby, the means for directing

against the articles a current of air in order to more rapidly chill them is brought into operation.

The accompanying drawings illustrating, as above indicated, that embodiment of the invention adapted to coating or galvanizing open-ended receptacles, such as pails; are as follows,

Figure 1 is a top view or plan of a machine by means of which my improved process of galvanizing may be practiced. Fig. 2 is a longitudinal sectional view of the parts seen in Fig. 3. Fig. 3 is an enlarged side view of one of the withdrawing arms for removing the articles from the bath. Fig. 4 is a side elevation of the machine showing the receptacle or vat for the molten metal, comprising the galvanizing bath, in section. Fig. 5 is a detailed plan view of the left hand end of the frame E² and the means for supporting the same from the side wall of the vat. Fig. 6 is an elevation of the end of the machine from which the finished articles are withdrawn. Fig. 7 is a sectional view taken on line x—x of Fig. 4 showing particularly the carrier and its actuating mechanism. Fig. 8 is a view of one of the bearings for supporting the shaft carrying the withdrawing arms for removing the pails from the cradle that operates to raise them out of the bath. Figs. 9 and 10 are slightly enlarged sectional views taken, respectively, on lines x¹—x¹ and x²—x² of Fig. 4. Fig. 11 is a plan view of the scraper bar used in my machine. Fig. 12 is a view from the left, with reference to Figs. 1 and 4, of the mechanism for cooling the pails as they are being withdrawn from the coating apparatus and just before they are delivered to a suitable table or platform therefor. Fig. 13 is a view from the right of the parts seen in Fig. 12 and shows, also, in outline the vat for holding the molten metal. The right hand withdrawing arm and the jaw operating cam are removed. Fig. 14 is an enlarged sectional view taken along the line x³—x³ of Fig. 13 of the right hand easing F³ and the right hand cooperating swinging member G seen in Fig. 12. Figs. 15 and 16 are transverse sectional views of the member F³ taken along the line x⁴—x⁴ of Fig. 12 with the member G differently disposed angularly relative to the member F³ of each of the figures.

Similar parts are designated by similar

reference characters throughout the several figures of the drawings.

Referring to the drawings. In practicing my invention, the articles *b* to be galvanized are placed by hand in a suitable carrier or conveyer *A* which may be actuated, preferably by means of suitable mechanism hereinafter described, on horizontal tracks *A*¹ to and from a position directly over the vat *B* containing the galvanizing bath. The pails or like articles *b* to be galvanized are forced from the carrier *A* by reciprocating members *C* into a vertically reciprocating cradle *D* upon the lateral supporting arms *d* and beneath depressing arms *d*¹ carried on the uprights *d*² thereof which are secured to and extend downwardly from the horizontal member *d*³.

The members *C* and cradle *D* are actuated by mechanism hereinafter described, coöperatively with each other and the carriage *A* in such a manner that, when the carriage *A* with the articles to be galvanized thereon is brought to a position directly over the galvanizing bath *B*, the carriage remains in this position with the articles to be galvanized in registration with the members *C* and cradle *D* while such members *C* are moved transversely across and above the bottom 30 of the carriage *A* to force the pails *b* therefrom upon the lower supporting arms *d* of the cradle *D*.

Immediately after the pails are deposited in the cradle *D*, the members *C* are withdrawn to the left and held in their initial positions out of the path of the carriage *A* which is then returned to its initial position to receive additional pails while the cradle *D*, previously held in its uppermost position for the reception of the pails from the carriage, is forced downwardly carrying the pails with it into the galvanizing bath in the vat *B*, the arms *d*¹ serving to engage the upper sides of the pails to force them, against their own buoyancy, into the galvanizing bath.

The distance between the arms *d* and *d*¹ of the cradle *D* is just sufficient to receive between them the pails *b*, and the upper arms *d*¹ are curved upwardly from their junctions with the upright portions of the cradle so as to allow the pails to readily ride out from thereunder by their own initial buoyancy resulting somewhat from the angle of their immersion relative to the surface of the bath when first depressed. The submerged pails then gradually settle or gravitate, to substantially the positions shown in dotted lines, upon a lower and underlying grid or support consisting of the series of bars *E* comprising horizontally extending portions of the inclined bars *E*¹ onto and along which, in the first place, the pails are forced by the upper arms *d*¹ of the cradle so as to free said pails from the path

of the lower arms *d* of the cradle when the same is moved upwardly for the reception of additional pails.

The bars *E* are formed integrally with the bars *E*¹ and comprise continuations thereof, and the bars *E*¹ are secured at their upper right hand ends, as seen in Fig. 4, to the right hand side wall of the open frame *E*² which, in turn, is supported at the right by a flange *e* resting on the top of the right hand end wall of the vat *B*, and, at the left, as seen in Figs. 4 and 5, by lugs *e*¹, carried by the frame member *E*², which rest upon brackets or hooks *e*², supported from the side walls of the vat *B* near its center. This frame work *E*² is open, that is, without a bottom in order that an unobstructed path therethrough may be provided for the pails in their downward course as carried by the cradle *D*. This frame *E*² is to contain the liquid flux which, being lighter than the liquid metal beneath, floats upon the surface thereof. The dotted lines *e*³ and *e*⁴ in Fig. 4 show approximately the levels of the upper surface of the flux in the frame *E*² and of the galvanizing bath in the vat *B*.

On account of the buoyancy of the pails as they enter the bath, there is very little pressure exerted upon the inclined portions *E*¹ of the bars *E* and again, on account of the fact that the pails, even if made of very heavy stock, weigh but little in the bath and on account of the further fact that the bars *E* and *E*¹ weigh but little when in the bath, such bars need to be supported only at their right hand ends and, being formed of angle iron, they are sufficiently rigid to retain their shape and remain in place when secured, as shown, by bolts or rivets to the right hand side wall of the flux carrying frame as above noted.

The pails, after they have settled on the supporting bars *E* within the bath, are moved through the bath, in the direction of their open ends, along and on said bars *E* by a horizontally and vertically movable cradle supported by and between two side bars *R* which have centrally disposed horizontal portions and upwardly and outwardly inclined portions at the ends of the horizontal portions. The horizontal portions of the bars *R* normally lie somewhat below the bars *E* and, supported on straps *r*² extending between them, there are seen short bars *r*¹ provided with upwardly projecting fingers *r* arranged in two series, spaced a distance apart somewhat greater than the length of the pails, and disposed at opposite ends thereof when such pails rest upon the bars *E* at the bases of the inclined portions *E*¹.

The cradle, comprising the bars *R* and parts carried thereby, is actuated, by mechanism hereinafter described, both vertically and horizontally. The vertical movement

brings the right hand fingers r , engaging between the bars E of each pair, into engagement with the closed ends of the pails so that, when the frame or cradle carried by the bars R is moved to the left, horizontally, a distance corresponding substantially to the distance between the two series of fingers r , the pails engaged by the fingers of the right hand series will be moved a corresponding distance to the left still resting upon the bars E . At the next similar movement of the bars R , the fingers r of the left hand series will act similarly upon the first named pails, or upon any pails which have been previously advanced upon the supporting bars E by the right hand series of fingers r , and deposit them into a vertically movable cage T ; and at the same time, the right hand fingers r will advance the second or succeeding series of pails to the position from which the first series has just been moved. Of these fingers r , there are provided for each pail to be engaged thereby, three in the left hand series and three in the right hand series. The center ones for engaging each pail, as seen in Fig. 9, are arranged to engage between the corresponding bars E , while the finger on either side of such central one engages outside of such corresponding bars E and also outside of the path of the bars d^6 of the cradle D . This is in order that some one or more of the three fingers r for each pail may be certain to engage and properly advance the pail at its right hand or closed end. The pails are thus moved step by step through the bath from right to left, being delivered thereto by the cradle D at one end and withdrawn at the other end by the cage of which the bars T comprise the bottom. This cage is reciprocated vertically, by mechanism hereinafter described, and so timed in its action that the bars comprising its bottom are disposed in a plane beneath the supporting bars E , while the bars R carrying the fingers r are feeding the pails thereto.

After each series of pails is deposited upon the vertically reciprocating bars T , the latter are elevated while the bars R are being returned to receive another series of pails. When the pails are elevated by the bars T to a predetermined position, the upper edge of the open end of each pail is caught between a pair of suitable gripping jaws h and h' , mounted on the outer ends of arms H secured upon a rock shaft s^6 , and are thereby lifted out of the bath and deposited right side up upon an exterior support L , as best shown in Fig. 4, whereupon the gripping jaws are released and returned to their starting positions ready to receive another pail or series of pails.

During the forward operation of the arms H , and while the pails are held by

the gripping jaws carried thereby, the pails are exposed to a strong current of air for the purpose of more rapidly chilling them, the construction and operation of the means for effecting which will be more fully explained later.

The gripping jaws h and h' and their arms H are actuated by suitable mechanism synchronized in their operation with those previously referred to, and they may be actuated from the same source, as a cone pulley J , which in turn may be connected by a belt to any available source of power, not shown. This pulley J is secured upon a suitable shaft j revolvably supported, in suitable bearings, and having thereon a pinion k meshing with a gear K on a shaft M , journaled in suitable bearings m upon a main supporting frame N , for transmitting power to the several mechanisms previously referred to.

The tracks A^1 for the carriage A may preferably be channel irons properly spaced apart to receive rollers a on the upper portion of the carriage frame and extend some distance beyond the vertical plane of the vat B and toward the operator, as seen in Fig. 1. Mounted upon the extreme opposite ends of the track A^1 are bearings a^1 in which are journaled shafts carrying suitable sprockets or drums a^2 connected by a chain A^2 and having its ends attached to the ends of the carriage A , as seen in Figs. 6 and 7.

A pinion a^3 is secured to the shaft carrying the rear sprocket wheel a^2 and meshes with the sliding rack a^4 , the latter having one end slotted to receive the shaft M upon which it is guided, and also provided with a roller or stud a^5 which rides in a grooved cam P , as best seen in Fig. 7, said cam being mounted directly on the shaft M to rotate therewith and thereby reciprocate the sliding rack a^4 to rotate the sprockets a^2 and thereby reciprocate the carriage A . The cam P has two portions of approximately equal angular extent concentric with the shaft M to permit the carriage A to remain at rest for a sufficient period at each end of its course.

The mechanism for reciprocating the cradle D is as follows:—Secured to the shaft M is a worm gear v meshing with a similar worm gear v^1 on the shaft s which is journaled in suitable bearings m^1 on the main frame N and provided with crank arms d^2 which are connected by links d^3 to a cross head d^4 having attached directly thereto the verticals d^6 movable vertically on suitable guides d^5 . The crank arm d^2 , the throw of which is sufficient to effect the desired vertical movement of the parts, is shown in Fig. 4 in position to hold such parts in their uppermost positions ready to receive the pails from the carrier A .

The members C for forcing the pails from

the carriage A, are mounted upon the lower ends of the parallel rock arms c, one of which is provided with a toothed segment c¹ mounted in a shaft s¹ and meshing with a similar segment c² on the stud c³, the latter in turn mounted in the main frame N. The segment c² has a slotted arm c⁴ to receive a stud c⁵ on the horizontal sliding bar C¹. This bar C¹ is guided in suitable ways c⁶ and 10 c⁷ on the main frame N and is provided with a lengthwise slot c⁷ for receiving a transverse shaft s¹. Mounted upon this bar C¹ is a roller or stud c⁸ which rides in a grooved cam P¹ mounted upon and rotated with a 15 shaft s¹ to engage said roller and thereby reciprocate the bar c¹ which, in turn, causes a rocking motion of the segments c¹ and c² respectively, for reciprocating the members C.

The cradle carried by the bars R is actuated vertically by opposite sets of bell crank levers r¹ and links r² pivotally suspended from the lower ends of such levers and also pivotally attached to the bars R at their left hand ends and to the extensions thereof to 20 the right of and above the vat B. These bell crank levers r¹ are secured to the opposite ends of parallel transverse rock shafts s² and s³ and are connected for simultaneous action by bars r³. The bell crank levers r¹ 25 are operated simultaneously by a reciprocating sliding bar R¹, which is guided in suitable ways r⁴ on the main frame N, and is operated by the crank arm r⁵ on the shaft s². This sliding bar R¹ is moved back and forth 30 by a suitable cam P² engaging a stud or roller on the bar R¹.

Horizontal rocking motion is imparted to the bars R¹ by means of a rock shaft s⁴ having crank arms r⁶ and r⁷ thereon, the 40 arms r⁶ being located at opposite ends of the shaft s⁴ and adjustably connected at their lower ends to the arms R, as seen in Figs. 1 and 4. The arm r⁷ is pivotally connected to a bar R² which is guided to reciprocate horizontally in suitable ways on the main frame N and is actuated by a grooved cam or concentric P³, as seen in Figs. 1 and 4.

Both of the cams P² and P³ are mounted upon the same transverse rotary shaft s⁵ 50 which is journaled upon the main frame N and is provided with a worm gear v³ meshing with a similar worm gear v² on the main shaft M, thereby imparting continuous rotary motion to both of the cams P² and P³ 55 by which the levers r¹ and r⁷ are operated to vertically and horizontally reciprocate the bars R.

I will now describe the mechanism for withdrawing the pails from the bath. A 60 series of obliquely disposed channel bars T are supported by the straps T¹ secured at their upper ends to the bars U between which there is secured the transverse bar U¹ from and above which there is secured 65 the cross bar U² by means of the bolts u.

Guide rods t⁵ are secured in the main frame N to constitute vertical guides for and upon which the members U¹ and U² vertically reciprocate to properly control the movements of the bars T. A grooved cam P⁴ is 70 mounted upon and rotates with the shaft s¹ and engages a roller or stud upon the outer end of the lever formed on or carried by the curved shaft T² working in bearings t and provided at its ends beyond the bearings with arms t⁶ each having an extension t¹ connected by links t² to one of the members U. The extensions t¹ are adjustable lengthwise of the arms t⁶ for varying the amount of the movement of the member U 75 through the medium of pinions t³ meshing with toothed racks on the extensions t¹, said pinions being secured upon a common shaft and adapted to be rotated by hand to effect the desired adjustment, after which the extensions are each held in adjusted position by a clamping screw t⁴.

The cams P¹ and P⁴ are mounted upon the transverse shaft s¹ driven from the main shaft M by intermeshing gears v⁴ and v⁵, 80 having their teeth disposed at an angle of 45° and substantially the same as the gears v and v¹ and v² and v³ for transmitting rotary motion from the main driving shaft M to the shafts s² and s⁴ respectively. 85

I will now describe the means for actuating the rocking arms H, best seen in Figs. 1, 2, 3, 4 and 6. The bars O are caused to reciprocate vertically in the guides O¹ by means of the grooved cam P⁶ on the shaft 100 M engaging a roller o on the cross bar O² connecting the arms O. Toothed racks O³ are arranged to reciprocate in the guides O¹ parallel with the bars O and are pivotally connected to the bars O by means of the links o¹ and o². The link o¹, near the observer in Fig. 4, has an arm O⁴, constituting such link a bell crank lever, and this arm has therein a slot extending lengthwise of the arm to receive an adjustable roller or 105 pin o³ which engages in the cam slot o⁴ in the plate V. The plate V is adjustable vertically on the plate V¹, which in turn is adjustable obliquely on the plate V², which is supported upon a bracket V³ mounted on 110 the frame N of the machine. The toothed racks O³ mesh with pinions or toothed segments o⁵ on the shaft s⁶ to which the arms H are secured. The shaft s⁶ is mounted in bearings formed in the brackets m³ secured to the upright end members of the frame N 115 of the machine. The cam P⁶ is conformed so as to cause each arm to be swung through practically three quarters of a revolution that is, from the horizontal position in 120 which it receives the pail to the vertical position in which it discharges the pail, as seen in Fig. 4. It will be seen that, by means of the above construction, the racks O³ will be reciprocated with the bars O and 125

the receiving platform L. Immediately thereafter, as the arms H are returning to receive and engage another set of pails, the segmental opening through the disk I permits an angular movement of the head g in advance of the disk I and causes the closing of the passage way from the pipe F² through the cylinder F³ into the cylinder G so that there is no discharge of the air through the nozzles n until after the next set of pails has been engaged and the parts reach approximately the position indicated in Fig. 13. This operation is repeated of course for each set of pails as they are removed.

As the operations of the different parts of my mechanism have been sufficiently explained, it is believed that the construction and operation of my machine, as a whole, is sufficiently clear, from the foregoing description, to call for no further explanation herein.

What I claim is:

1. A galvanizing apparatus comprising a galvanizing bath and means for automatically immersing the articles therein and withdrawing them therefrom and, in combination therewith, means for variably predetermining the rate of movement of the automatic withdrawing means independent of any change in the rate of movement of the other elements of the apparatus.

2. In a galvanizing apparatus, the combination of a vat for the galvanizing bath, an immersing cradle movable into and out of the bath, means for actuating said cradle, means for conveying the articles to be galvanized thereto, and additional means for forcing such articles from the conveyor into the path of said cradle.

3. In a galvanizing apparatus, the combination of a vat for the galvanizing bath, a supporting frame within the vat and below the surface of the bath, an immersing cradle movable into and out of the bath, such cradle having arms adapted in the downward movement of the cradle to force the articles outwardly therefrom, means for forcing the articles along on said supporting frame, and an oscillatory, gripping arm and means for actuating the same, such arm adapted to engage the articles and remove them from the bath.

4. In a galvanizing apparatus, the combination of a vat for the galvanizing bath, a supporting frame within the vat and below the surface of the bath, an immersing cradle movable into and out of the bath, such cradle having arms adapted in the downward movement of the cradle to force the articles outwardly therefrom, means for forcing the articles along on said supporting frame, an oscillatory gripping arm and means for actuating the same, such arm

adapted to engage the articles and remove them from the bath, and means for removing matter from the surface of the bath just before the withdrawal of the articles therefrom.

5. In a galvanizing apparatus, the combination of a vat for the galvanizing bath, a supporting frame within the vat and below the surface of the bath, an immersing cradle movable into and out of the bath, such cradle having arms adapted in the downward movement of the cradle to force the articles outwardly therefrom, means for forcing the articles along on said supporting frame, an oscillatory, gripping arm and means for actuating the same, such arm adapted to engage the articles and remove them from the bath, and means for varying the rate of movement of such arm relative to the other elements of the apparatus and during the withdrawal of the articles thereby from the bath.

6. In a galvanizing apparatus, the combination of a vat for the galvanizing bath, a supporting frame within the vat and below the surface of the bath, an immersing cradle movable into and out of the bath, such cradle having arms adapted in the downward movement of the cradle to force the articles outwardly therefrom, a vertically and horizontally movable cradle below said supporting frame for forcing the articles along and from said frame, a vertically movable rack adapted to receive the articles from said frame and raise them to the surface of the bath, an oscillatory gripping arm and means for actuating the same, such arm adapted to engage the articles and remove them from the bath, and means for removing matter from the surface of the bath just before the withdrawal of the articles therefrom.

7. In a galvanizing apparatus, the combination of a vat for the galvanizing bath, a supporting frame within the vat and below the surface of the bath, an immersing cradle movable into and out of the bath, such cradle having arms adapted in the downward movement of the cradle to force the articles outwardly therefrom, a vertically and horizontally movable cradle below said supporting frame for forcing the articles along and from said frame, a vertically movable rack adapted to receive the articles from said frame and raise them to the surface of the bath, an oscillatory, gripping arm and means for actuating the same, such arm adapted to engage the articles and remove them from the bath, means for varying the rate of movement of such gripping arm relative to the other elements of the apparatus and during the withdrawing of the articles thereby from the bath, and means carried by said vertically and hori-

at the same rate of travel until the roller o^3 engages the cam in the slot o^4 in the plate V whereupon the consequent throw of the lever o^4 causes the racks O^3 to travel slower than the bars O until the crest of the cam is reached and thereafter correspondingly faster.

By adjusting the roller o^3 in the slot in the lever o^4 , the amount of such retardation is changed. The plate VI is adjusted to compensate for the adjustment of the roller o^3 . Adjusting the plate V changes the time at which the retardation begins, for any fixed position of the other co-operating parts. By adjusting the parts as above described so that the movement of the arms H will be retarded just as the pails are being withdrawn from the bath, the thickness or depth of the coating will be less than it would if the pails or articles being galvanized were more quickly withdrawn from the bath. As the pails are lifted from the bath by the bars T, it is desirable to remove the flux and other floating matter on the surface of the galvanizing bath to prevent its adhering to the pails as the latter are withdrawn, and for this purpose, I provide a suitable horizontally disposed U-shaped scraper bar r^3 secured to arms r^1 formed integrally on and extending to the right from and in the same plane with the left hand ends of the bars R, as seen in plan view in Fig. 11, and arranged to travel through, across and near the upper surface of the bath as the bars R move from left to right and before the bars T are elevated to bring the pails thereon within the range of the gripping jaws h and h^1 .

In order that the gripping jaws may effectively grip portions of the edges of the pails of the different thicknesses, such for instance, as rims of different sizes, one of the jaws of each pair as h is made yielding or operable against the action of the spring h^2 through the supporting and guiding rods h^3 ; while the other jaw h^1 , which is movable to and from the jaw h , is hinged at one end to the outer end of the arm H and is provided with a toothed segment h^4 meshing with the reciprocating rack h^5 , the inner end of which is provided with a roller or stud h^6 which rides in a grooved rim h^7 . The cam h^7 is prevented from rotation by being secured to the cross bar h^8 supported on the under sides of the brackets m^2 and is so arranged as to operate against the movable jaw to close the same upon the rim of the pail, when the arm H is in its receiving position, and to remain closed during the greater portion of the movement of said withdrawing arm and to open when said arm reaches the position for discharging the pails.

Refer now to Figs. 12 to 16 inclusive. A shaft s^8 is supported in bearings m^2 secured

to the left hand end standards of the frame N and to these standards there are also secured, by means of brackets f, the fan cases F located within which are suitable fans F¹ secured on the shaft s^8 which is operated by means of a pulley F⁴ thereon in the usual way. Each of these fan cases F has the usual central inlet openings and has an outlet pipe F² which terminates in a cylinder member F³ closed at one end and having its open end engaging within the flange g¹ on a nearly similar cylinder member G. There are two of these cylinders G and two of the cylinders F³ and pipes F² leading thereto. The cylinders F³ and pipes F² are suitably supported so that the cylinders F³ are positively held in substantially concentric relation to the shaft s^8 . On this shaft s^8 are secured the cylinders G opening upwardly into a continuous pipe G¹ provided with three discharge nozzles n conformed to direct streams of air against the pails b. The pipe G¹ is strapped to the arms H so as to be carried therewith and the cylinders G, also, are thus supported on and carried with the shaft s^8 upon which the arms H are secured.

The heads of the cylinders G farthest apart, being the ones adjacent to the cylinders F³, as seen at g, are provided with four openings formed as indicated in Figs. 14, 15 and 16, and adapted to co-operate with floating disks I, having similar openings therein, in the following way, viz.:—each of the disks I is free to revolve upon the shaft s^8 and is held in place against endwise movement thereon and against the head g of the cylinder G by means of an adjustable collar y. Each of the disks I is supported freely upon the shaft s^8 , in such a way that it is carried by and with such shaft and the cylinders G moving angularly therewith only when the pins g² engage against the disks I at one end of the peripherally formed slots therein.

Projecting outwardly from each cylinder head g is seen a pin g² engaging through a segmental opening therefor in the outer periphery of the disk I, and the extent of this segmental opening is such that the relative movement permitted between the disk I and the adjacent head g of the corresponding cylinder G is sufficient to cause the openings through the disk I and the head g to register or to be alternately disposed so as to close the passage from the pipe F² and cylinder F³ into the cylinder G.

The angular adjustment of the parts just described is such that, when the arms H reach the position substantially as indicated in Fig. 13, the passageway through each of the pipes F² and cylinders F³ and G into the pipe G¹ is free and open and of course remains open until the pails, by the further movement of the arms H, are delivered onto

zontally movable cradle for removing matter from the surface of the bath just before the withdrawal of the articles therefrom.

8. In a galvanizing apparatus, the combination of a vat for the galvanizing bath, means for feeding the articles to be galvanized into the bath, and additional means for withdrawing the galvanized articles from the bath comprising an oscillatory gripping device movable through an arc of at least 180° for inverting said articles as they are withdrawn from the bath, and means for varying the rate of movement of said gripping device relative to the other elements of the apparatus and during the withdrawal of the articles from the bath.

9. In a galvanizing apparatus, the combination of a vat for the galvanizing bath, means for feeding the articles to be galvanized into the bath, and additional means for withdrawing the galvanized articles from the bath comprising an oscillatory gripping device movable through an arc of at least 180° for inverting said articles as they are withdrawn from the bath, and means for rapidly chilling the articles comprising automatically operating mechanism for directing streams of air against the articles just after they have been removed from the bath and while they are being swung to their inverted position.

10. In a galvanizing apparatus, the combination of a vat for the galvanizing bath, means for feeding the articles to be galvanized into the bath, additional means for withdrawing the galvanized articles from the bath comprising an oscillatory gripping device movable through an arc of at least 180° for inverting said articles as they are withdrawn from the bath, and means carried by said gripping device and the shaft upon which it rotates for directing a stream of air against said articles, for the purpose of chilling them, just after they

have been withdrawn from the bath and 45 while they are being swung to their inverted position, all substantially as described.

11. A galvanizing apparatus comprising, in combination, a vat for the galvanizing bath, a reciprocatory conveyer for the articles to be galvanized, an immersing cradle movable into and out of the bath, such cradle having arms adapted in the downward movement of the cradle to force the articles outwardly therefrom, means for 50 discharging the articles from said conveyer into the path of said immersing cradle, a supporting frame within the vat and below the surface of the bath, a vertically and horizontally movable cradle below said supporting frame adapted to intermittently advance the articles along said frame, a vertically movable rack adapted to receive the articles from said frame and raise them to the surface of the bath, withdrawing means 55 comprising an oscillatory gripping device movable through an arc of at least 180° for inverting the articles as they are withdrawn from the bath, means for varying the rate of movement of said gripping device relative to the other elements of the apparatus and during the withdrawal of the articles from the bath, means carried by said gripping device and the shaft upon which it rotates for directing a stream of air against 60 said articles, for the purpose of chilling them, just after they have been withdrawn from the bath and while they are being swung to their inverted position, and means carried by said vertically and horizontally 65 movable cradle for removing matter from the surface of the bath just before the withdrawal of the articles therefrom, all substantially as described.
